UNITED STATES PATENT OFFICE.

WILLIAM F. WEATHERS, OF JACKSON, MICHIGAN.

PAIL-HANGER.

986,660.

Specification of Letters Patent. Patented Mar. 14, 1911.

Application filed August 27, 1910. Serial No. 579,268.

To all whom it may concern:

Be it known that I, WILLIAM F. WEATHERS, a citizen of the United States of America, residing at Jackson, in the county of 5 Jackson and State of Michigan, have invented certain new and useful Improvements in Pail-Hangers, of which the following is a specification, reference being had therein to the accompanying drawings.

10 This invention relates to a pail holder adapted for painters' use and other purposes where it is desirable to suspend pails from a ladder or scaffold within easy reach of the user.

15 The invention consists in the matters hereinafter set forth and more particularly pointed out in the appended claims.

Referring to the drawings, Figure 1 is a view of a holder that embodies features of 20 the invention with pails thereon in position; Fig. 2 is a view in detail of a retaining ring and pail; Fig. 3 is a view in detail of a hanger; Fig. 4 is a view in detail of a hanger hook; Fig. 5 is a view in detail of a 25 brush holder; Fig. 6 is a view in detail of a base plate.

As herein illustrated, a base plate 1, circular in outline with a pair of oppositely disposed segmental notches cut therefrom 30 retains a pair of cylindrical bands 2 beaded at their margins which are retained in the segmental notches of the base 1 by tongues 3 whose ends pass under the bead, the remaining marginal portions of the notches 35 being snapped over the beads. An upright block 4 is secured on end centrally on the base between the bands 2 provided with bolt holes 5 through which bolts are passed that secure the upper portions of the bands in 40 place.

A hanger strap is bent between its ends into a pair of parallel arms 6 secured on opposite sides of the block 4, as by screws 7 or the like, and formed above the block into an 45 oval loop 8 provided with a longitudinal slot 9 in its upper portion. A hanger or painter's hook 10 has a screw-threaded shank 11 which may be passed through the slot 9 where it is secured as by suitable nuts 50 12 or the like so as to tilt in either direction. Each band is provided with a brush holder that is preferably formed of a piece of 55 spring wire bent between its ends into slightly outwardly curved spring arms 13 with mating looped ends 14 and a central eyelet 15 secured against the side of the

band by bolts 16. The bands 2 are proportioned to receive a paint pail or the like and when the apparatus is assembled, it forms a ready means for carrying paint pails or the 60 like and holds them in any desired position either on a scaffold or ladder. There are no rivets to rust out or work loose the bolts enabling the parts to be renewed if necessary, and the whole forms a simple and effective 65 device for painters' use.

Obviously changes in the details of construction may be made without departing from the spirit of the invention and I do not care to limit myself to any particular 70 form or arrangement of parts.

What I claim as my invention is:—

1. A paint pail holder comprising a base, 75 pail collars secured thereto, an upright standard between the collars, a hanger on the standard having a looped and slotted upper end, and a painter's hook adjustably secured in a slot of the hanger.

2. A paint pail holder comprising a plate, 80 a standard secured thereto, pail collars interlocked at their lower margins with the margins of the plate and secured to the standard, a hanger strip secured to the standard and provided with a looped and slotted upper end, and a painter's hook adjustably secured in the slotted hanger end.

3. A paint pail holder comprising a plate 85 having diametrically opposite, concave segmental notches with central tongues, collars fitting the notches with beaded margins interlocked by the tongues and adjacent margins 90 of the notches a standard on the plate between the notches, a hanger strip extending above the notches, a painter's hook adjustably secured in the upper end of the 95 hanger, and brush holders on the collars.

4. A paint holder comprising a plate having diametrically opposite concave segmental notches with central tongues, collars fitting the notches with beaded margins interlocked by the tongues and adjacent margins 100 of the notches, a standard on the plate between the notches, a hanger strip bent between its ends into a pair of parallel arms secured to the standard with a connecting 105 slotted loop above the standard, a painter's hook having a screw-threaded shank engaging the loop slot, nuts for securing the shank in the slot, and brush holders on the collars.

5. A pail hanger comprising a base plate 110 having a pair of diametrically opposite, segmental concave notches with a central tongue

extending from the margins of each notch, pail collars having beaded lower margins each fitting a plate notch and interlocking with the tongue and margin thereof, a standard on the plate between the collars, a hanger strip embracing the standard and having a slotted loop above the standard, a painter's hook engaging the loop slot, nuts securing

the hook in the slot, and spring brush holders on the collars. 10

In testimony whereof I affix my signature in presence of two witnesses.

WILLIAM F. WEATHERS.
